SWITCH

Howard W. Graybill, Wilkinsburg, Pa., assignor to
Westinghouse Electric & Manufacturing Company, East Pittsburgh, Pa., a corporation of Pennsylvania

Application March 6, 1942, Serial No. 433,552

17 Claims. (Cl. 200—48)

This invention relates, generally, to electric switches and, more particularly, to disconnecting switches of the high pressure contact type.

Many types of high contact pressure disconnecting switches have been proposed, and this invention is especially concerned with certain improvements in the type of switch wherein the blade is pivotally movable to and away from a position in proximity with line contacts, and is rotatable about its longitudinal axis into and out of high pressure engagement with said contacts.

One object of this invention is to provide a disconnecting switch of the type wherein a blade is pivotally movable about a transverse axis to and away from a position in proximity with a line contact and rotatably movable about a longitudinal axis of the blade into and out of high pressure engagement with said contact, with means for positively causing said movements to occur sequentially.

Another object of this invention is to provide a disconnecting switch of the type wherein a blade is pivotally movable about a transverse axis to and away from a position in proximity with a line contact and rotatably movable about a longitudinal axis of the blade into and out of high pressure engagement with said contact, with means for positively preventing substantial movement about the longitudinal axis unless the blade is at said position in proximity with said line contact.

Another object of this invention is to provide a disconnecting switch having novel means for actuating the switch blade and controlling the movement thereof to open and closed circuit positions.

Another object of this invention is to provide a novel type of disconnecting switch having a blade movable into and out of high pressure engagement with spaced line contacts.

These and other objects of this invention will become more apparent upon consideration of the following detailed description of a preferred embodiment thereof when taken in connection with the attached drawing, in which:

Figure 1 is a side elevation view partially in section of a switch constructed in accordance with this invention;

Fig. 2 is a sectional view of the switch shown in Fig. 1 taken substantially on the line II—II thereof;

Fig. 3 is an enlarged section view of the switch blade with the blade support shown in elevation

taken substantially on the line III—III of Fig. 1; and

Fig. 4 is a transverse section view taken substantially on the line IV—IV of Fig. 1.

The specific switch illustrated embodying this invention may be mounted on any desired support, such, for example, as the channel support 2. The switch proper is supported on a pair of spaced insulators 4 and 6 rigidly secured on channel base 2 by any desired means (not shown), such, for example, as by bolts or the like. A contact assembly 8 is adapted to be mounted on insulator 4 and secured thereto, for example, as by bolts 10. The contact assembly 8 is preferably made of copper or other good conducting material, and includes spaced contact jaws 12 and 14 extending outwardly from the base of the assembly and having the outer ends thereof flared to facilitate the entrance of a switch blade therebetween. Contact jaw 14 is preferably provided with a series of projections or teeth 16 on the inner side thereof for a purpose to be hereinafter described. Contact assembly 8 further includes a laterally extending terminal pad 18 for the connection of a line conductor thereto.

A third insulator 20 is adapted to be rotatably mounted in a bearing 22 provided in supporting base 2 and carries an actuating crank 24 which may be manually moved to rotate the insulator, or which may be connected to remotely operated linkage mechanism. A blade and contact support 26, generally of inverted U-shape in cross section, is adapted to be supported on insulators 6 and 20. Blade support 26 includes a base portion 28 and spaced sides 30 extending towards supporting insulators 6 and 20 and extended beyond base 28 towards insulator 4. The portions of side walls 30 extending beyond base 28 towards insulator 4 are connected at one side by a mounting plate 32 secured to insulator 6 as by bolts 34. The other side of the extended portions of side walls 30 are connected at the outer end by a contact supporting plate 36 having an integral stop flange 38 disposed between spaced contact jaws 40, also preferably formed integral with blade support 26.

The switch blade 42 is adapted to be mounted at one end in a journal bearing 44 provided in the base portion of a generally U-shaped pivot supporting bracket 46. The pivot supporting bracket 46 is pivotally mounted between the extended side walls 30 of blade support 26 on a pivot pin 48. Switch blade 42 is maintained against endwise movement in journal bearing 44 by a head 50 formed on the blade at the inner

side of the base of pivot supporting bracket 48, and at the other side of bearing 44, the blade is provided with oppositely extending contact flanges 52 for cooperation with contact jaws 40, as will hereinafter more fully appear. Outwardly of contact flanges 52, blade 42 is provided with a guide supporting block 54 secured thereto in any desired manner, such, for example, as by welding or the like. Guide block 54 is adapted to support a slotted guide 56 which may be formed by relatively rigid strap or rod material bent upon itself with the ends secured in apertures in guide supporting block 54, for example, as by set screws 58. It will be noted that guide 56 provides a slot including a transversely curved portion 60 formed on the arc of a circle having its center on the longitudinal axis of blade 42, and an end portion curved substantially longitudinally of the blade on the arc of a circle having blade pivot 48 as its center. A guide pin 61 fixed to or formed integral with blade support 26 is positioned to enter the slot in guide 56 to cooperate therewith in guiding the movement of blade 42. Switch blade 42 is provided with a flattened end portion 62 having a relatively sharpened edge for a purpose to be hereinafter described.

Rotatable insulator 28 is provided with a shaft 64 secured to the outer end thereof projecting through an aperture provided in blade support 26, and this shaft terminates in a crank 66 for actuating the switch blade. Crank 66 is preferably associated with a connecting link 68 by a universal type joint 69, and connecting link 68 is, in turn, pivoted at 74 to the outer end of a guide link 70 pivotally supported on blade pivot 48. A blade actuating link 72 is also pivotally associated with pivot pin 74 and connected at a remote point, as by a ball and socket connection 76, with a crank 78 fixed on switch blade 42. Crank 78 may be rigidly secured to blade 42 or be formed integral with guide supporting block 54.

A compression counterbalancing spring 80 is provided within U-shaped blade support 26 to assist in opening the blade. Spring 80 bears at one end on an integral spring support lug 82 within blade support 26, and telescopically receives a supporting rod 86 at its other end. The supporting rod 86 is preferably pivotally mounted between the outer ends of U-shaped pivot supporting bracket 48. As shown, blade support 26 may include an integral terminal pad portion 88 for the connection of the other line conductor thereto.

In Fig. 1 of the drawing, the switch is shown in the closed circuit position. In this position, the flattened blade end 62, the largest dimension of which should be slightly in excess of the normal spacing of contact jaws 12 and 14, is positioned between these jaws transversely thereof so as to be in high pressure engagement therewith. Likewise contact flanges 52 adjacent the blade pivot have an extent slightly greater than the spacing of contact jaws 40, and these are positioned laterally between contact jaws 40 so as to be in high pressure engagement therewith. Accordingly, in the closed circuit position of the switch, the electric circuit may extend from one terminal pad 88 through blade support 26, contact jaws 40 thereon, to contact flanges 52, thence through blade 42, and portion 62 thereof to contact jaws 12, 14 and terminal pad 18.

Now if it is desired to open the circuit, this may be accomplished by rotating insulator 28 to cause a downward pull on connecting link 68 and a consequent counterclockwise rotation of supporting link 70 about its pivot 48. This will cause a pull to be exerted on actuating link 72 and,

consequently, tend to rotate the blade 42 through crank 78 about the longitudinal axis of the blade. This rotation of blade 42 about its longitudinal axis is permitted by curved portion 60 of guide 56 and will, of course, be limited to the extent of guide portion 60. This rotation may be any desired amount, and its purpose is to rotate the blade until end portion 62 and contact flanges 52 thereof are disposed at an angle to their respective contact jaws so as to release the high pressure engagement between these parts and permit the free removal thereof from between the jaws. It should be noted that during this initial rotation of blade 42 about its longitudinal axis, portion 60 of guide 56 also positively prevents any pivotal movement of the blade about pivot 48 because the guide portion 60 is formed on the arc of a circle having its center on the longitudinal axis of the blade. At the end of this first movement, guide 56 will have moved from the full-line position shown in Fig. 3 to the dotted line position wherein the end thereof is directly beneath guide pin 61 on support 26. When this position of the parts has been attained, further rotation of insulator 28 in the same direction and consequent further pull on actuating link 72 in the same direction, will cause blade 42 to pivot about pivot axis 48 to remove end portion 62 and contact flanges 52 from between their respective contact jaws. It should be noted that during this movement of the blade about its pivot 48, it is positively prevented from rotating about its longitudinal axis because guide pin 61 is then riding in the portion of guide 56 which is in a plane parallel with the blade and is curved solely on the arc of a circle having its center about blade pivot 48. Consequently, during the part of the blade movement about its pivot 48, end portion 62 and contact flanges 52 thereof are maintained in the inclined position, preferably about 60° from the position shown in Figs. 2 and 4, wherein they are freely movable into and out of the space between switch jaws 12, 14 and 40, respectively. Accordingly, in a circuit opening operation, the switch blade is first solely rotated about its longitudinal axis to relieve the contact pressure between the contact portions of the blade and their associated line contact jaws, so that thereafter the blade may be freely pivotally moved to a position spaced from both line contact jaws while holding the blade in the angular position relative to its longitudinal axis at which it is freely movable into and out of the space between the line contact jaws.

After the switch has been opened, it may be readily closed by merely rotating insulator 28 continuously in the opposite direction. This has the effect of first pivotally moving blade 42 about pivot 48 toward contact jaws 12, 14 and 40, while the blade is still held in the same angular position relative to its longitudinal axis because guide pin 61 is still riding in the outer end portion of guide 56. This angular position of the blade permits the end portion 62 of the blade and contact flanges 52 thereof to be freely inserted between their respective contact jaws into proximity therewith. At the end of pivotal movement of the blade about pivot 48, the blade engages stop flange 88 on contact supporting plate 86, and guide pin 61 comes to the end of the slot in the outer end portion of guide 56 so that pivotal movement of the blade in the closing direction is halted. Thereafter continued rotation of insulator 28 in the same direction causes

rotation of blade 42 about its longitudinal axis in a counterclockwise direction, as viewed in Fig. 3, or a clockwise direction, as viewed in Fig. 2, to rotate the blade until end 62 and contact flanges 52 thereof are positioned transversely of their respective contact jaws in high pressure engagement therewith. It will be observed that as this rotation of blade 42 about its longitudinal axis begins, the sharp side edge of end 62 of the blade will engage between teeth 16 on jaw 14 to hold this edge of the blade relatively stationary and thereby cause downward movement of the opposite edge of the blade into high pressure engagement with jaw 12 with a wiping action. It will be noted that in the closing movement of the blade, guide 58 operates to cause pivotal movement of the blade 42 about pivot 48 and about the longitudinal axis of the blade to take place in a predetermined sequence as in the opening movement of the switch, but in a reverse order.

In view of the foregoing, it is apparent that this invention provides a switch of the type wherein a blade is pivotally movable from a position spaced from a line contact to and away from a position wherein it is in proximity with such a line contact and thereafter is rotatably movable about its longitudinal axis into high pressure engagement with the line contact, with means for positively causing these two movements to occur in a predetermined sequence. This segregation of the two blade movements permits obtaining a relatively large amount of rotation of the blade about its longitudinal axis, all of which can be utilized when the blade is positioned in proximity to the aligned contacts to obtain the desired high pressure engagement of the blade with the line contacts. Furthermore, because this relatively large rotative movement of the blade about its longitudinal axis is confined to the blade position wherein it is in proximity with line contacts, it is possible to insure freeing of the blade from the line contacts so that it will be freely movable towards and away from the line contacts to insert an air gap in the circuit. Furthermore, by the construction disclosed, the blade is always maintained, during pivotal motion thereof, at the position relative to its longitudinal axis wherein the blade is freely movable into the space between the line contact jaws; thus, it is possible to eliminate jamming of the blade and failure to enter between the contact jaws due to angular displacement of the blade about its longitudinal axis.

Furthermore, this invention provides a switch of the above type having a bridging blade cooperative with a pair of spaced line contact jaws, thereby eliminating the necessity for flexible shunts at the blade hinge. Another result which is obtained by the switch of this invention, due to the large angular rotation of the blade about its longitudinal axis obtainable when the blade is positioned between line contact jaws, is in the accentuated wiping action obtainable, particularly when one jaw is provided with teeth, as shown in Fig. 2. This invention also comprehends certain novel supporting means for a switch blade and an actuating mechanism and arrangement of parts whereby a relatively simple, yet efficient, switch structure is obtained. In connection with the blade support, it is particularly to be noted that the support specifically disclosed provides a housing for the blade counterbalancing spring as well as for the guide 58, 75

at least in the closed circuit position of the switch.

Having particularly disclosed a preferred embodiment of the invention in accordance with the patent statutes, it should be understood that the invention is not to be limited to this particular embodiment because it will be obvious, particularly to persons skilled in the art, that many changes and modifications may be made in this particular embodiment without departing from the broad spirit and scope of this invention. Accordingly, it is desired that the invention be interpreted as broadly as possible and that it be limited only as required by the prior art.

15 I claim as my invention:

1. In a switch, a line contact, a blade member mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, actuating means for pivotally actuating said blade member to move said blade portion to and away from said position in proximity with said contact, and rigid means positioned adjacent the pivot axis of said blade member to engage said blade portion separately from the engagement of said actuating means and blade member for positively preventing substantial rotational movement of said blade portion during said pivotal movement of said blade member.

2. In a switch, a line contact, a blade member mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, and cooperating guide means fixed on said blade portion and on a fixed support, respectively, for positively preventing said rotational movement of said blade portion during pivotal movement of said blade member until said blade portion is in said position in proximity with said contact.

3. In a switch, a line contact, a blade member mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, and cooperating pin and guide slot means on said blade portion and a fixed support, respectively, for positively preventing said rotational movement until said blade portion is in said position in proximity with said contact.

4. In a switch, a line contact, a blade member pivotally mounted for movement to and away from one position at which it is in proximity with said contact, at least the portion of said blade member adjacent said contact at said one position of said blade member being rotatable about a longitudinal axis of said blade member into and out of high pressure engagement with said contact when said blade member is at said one position, means for actuating said blade member in a circuit opening operation to first rotate said blade portion out of high pressure engagement with said contact and to thereafter pivotally move said blade member to a position spaced from said contact, and rigid means adjacent the

pivot axis of said blade member snugly engaging means movable with said blade member for preventing said pivotal movement until said blade portion is rotated out of high pressure engagement with said contact.

5. In a switch, a line contact, a blade member mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, and rigid means adjacent the pivot axis of said blade member snugly engaging means movable with said blade member for preventing pivotal movement of said blade member in either direction when said blade portion is in said position in proximity with said contact.

6. In a switch, a line contact including spaced contact jaws, a blade member mounted for pivotal movement to and away from a position wherein a portion of said blade is disposed between said jaws, said blade portion being mounted for rotational movement about a longitudinal axis and having one transverse dimension greater than the other and slightly greater than the distance between said jaws, and rigid means snugly engaging a part movable with said blade member for positively positioning said blade portion at an angle at least during movement thereof into and out of the space between said jaws.

7. In a switch, a line contact including spaced contact jaws, a blade member mounted for movement to and away from a position wherein a portion of said blade is disposed between said jaws, said blade portion being mounted for pivotal movement about a longitudinal axis and having one transverse dimension greater than the other and slightly greater than the space between said jaws, means for positioning said blade portion at an angle at least during movement thereof into and out of the space between said jaws, and interlocking means on one edge of said blade portion and one of said jaws engageable by rotative movement of said blade portion toward a position at which it is transverse to said jaws to prevent movement of said one edge relative to said one jaw and cause the other edge of said blade to have high pressure wiping engagement with said other jaw.

8. In a switch, spaced supporting insulators, a line contact supported on one of said insulators, an inverted generally U-shaped support mounted on the other of said insulators, line terminal means on said support, a switch blade pivotally mounted between the leg portions of said support adjacent the end of said support nearest said contact, a second contact mounted on said support adjacent the pivot axis of said blade, said blade being pivotally movable into and out of engagement with said contacts, and counterbalancing means for said blade positioned within said U-shaped support at least in the closed position of the switch.

9. In a switch, spaced supporting insulators, a line contact supported on one of said insulators, an inverted generally U-shaped support mounted on the other of said insulators, line terminal means on said support, a switch blade pivotally mounted between the leg portions of said support adjacent the end of said support nearest said contact, said blade being pivotally movable into and out of engagement with said contact, and rotatably movable about a longitudinal axis

thereof, cooperable guide means on said support and blade for controlling the sequence of said pivotal and rotatable movements, and said guide means on said blade extending within said support at least in the closed position of the switch.

10. In a switch, spaced supporting insulators, a line contact supported on one of said insulators, an inverted generally U-shaped support mounted on the other of said insulators, line terminal means on said support, the leg portions of said support being extended in a direction toward said contact for pivotally mounting a switch blade therebetween, said blade being pivotally movable into and out of proximity with said contact, at least the portion of said blade engageable with said contact being mounted for rotational movement about a longitudinal axis for movement into and out of high pressure engagement with said contact when in proximity therewith, cooperating pin and guide slot means on said blade portion and support, respectively, for positively preventing said rotational movement until said blade portion is in said position in proximity with said contact, and the portion of said guide means on said blade portion adapted to extend between the legs of said support at least at the closed circuit position of said switch.

11. In a switch, a line contact, a blade member mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, and cooperating pin and slot means associated with said blade member, with said slot having connected angularly related portions for positively controlling said pivotal and rotational movements, respectively.

12. In a switch, a line contact, a blade member mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, cooperating pin and guide slot means on said blade portion and a fixed support, respectively, said slot having a portion concentric with said longitudinal axis to receive said pin when said blade portion is in proximity with said contact, and a connected portion of said slot being concentric with said pivotal axis to receive said pin during movement of said blade portion toward and away from said contact, to thereby positively control the angular position of said blade at all times.

13. In a switch, a line contact, a blade member mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, cooperating pin and guide slot means on said blade portion and a fixed support, respectively, said slot having a portion concentric with said longitudinal axis to receive said pin when said blade portion is in proximity with said contact, and a connected portion of said slot extending angularly with respect to said first slot portion to receive said pin during movement of said blade

portion toward and away from said contact, to thereby positively control the angular position of said blade at all times.

14. In a switch, a line contact including spaced contact jaws, a blade member mounted for movement to and away from a position wherein a portion of said blade is disposed between said jaws, said blade portion being mounted for pivotal movement about a longitudinal axis and having one transverse dimension greater than the other and slightly greater than the space between said jaws, means for positioning said blade portion at an angle at least during movement thereof into and out of the space between said jaws, and interlocking projection and recess means on one edge of said blade portion and one of said jaws, respectively, engageable by rotative movement of said blade portion toward a position at which it is transverse to said jaws to prevent movement of said one edge relative to said one jaw and cause the other edge of said blade to have high pressure wiping engagement with said other jaw.

15. In a switch, a line contact including spaced contact jaws, a blade member mounted for movement to and away from a position wherein a portion of said blade is disposed between said jaws, said blade portion being mounted for pivotal movement about a longitudinal axis and having one transverse dimension greater than the other and slightly greater than the space between said jaws, means for positioning said blade portion at an angle at least during movement thereof into and out of the space between said jaws, and a plurality of grooves on one of said jaws, one edge of said blade portion of a size and shape to be received in one of said grooves upon rotative movement of said blade portion toward a position at which it is transverse to said jaws to prevent movement of said one edge relative to said one jaw and cause the other edge of said blade to have high pressure wiping engagement with said other jaw.

16. In a switch, a line contact, a blade member

mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, actuating means for rotating said blade portion a predetermined amount when it is in said position in proximity with said contact, and rigid means positioned adjacent the pivot axis of said blade member to engage said blade separately from the engagement of said actuating means and blade portion for positively preventing pivotal movement of said blade member during said predetermined amount of rotation of said blade portion.

17. In a switch, a line contact, a blade member mounted for pivotal movement to and away from a position wherein a portion of said blade is in proximity with said contact, at least said blade portion being mounted for rotational movement about a longitudinal axis for movement into and out of high pressure engagement with said contact when in said position in proximity thereto, actuating means for rotating said blade portion a predetermined amount when it is in said position in proximity with said contact and for pivotally actuating said blade member to move said blade portion to and away from said position in proximity with said contact, and rigid means positioned adjacent the pivot axis of said blade member to engage said blade portion separately from the engagement of said actuating means and blade member for positively preventing substantial rotational movement of said blade portion during said pivotal movement of said blade member and for positively preventing pivotal movement of said blade member during said predetermined amount of rotation of said blade portion.

HOWARD W. GRAYBILL.
